UNITED STATES PATENT OFFICE.

THOMAS E. BARNES, OF UTICA, NEW YORK, AND BREWSTER C. SHETTER, OF LANCASTER, PENNSYLVANIA.

DISPENSING DEVICE.

1,319,264.

Specification of Letters Patent.

Patented Oct. 21, 1919.

Application filed March 6, 1919. Serial No. 280,973.

To all whom it may concern:

Be it known that we, THOMAS E. BARNES and BREWSTER C. SHETTER, citizens of the United States, and residents, respectively, of 5 Utica, in the county of Oneida and State of New York, and Lancaster, in the county of Lancaster and State of Pennsylvania, have invented certain new and useful Improvements in Dispensing Devices; and we do 10 hereby declare that the following is a full, clear, and exact description thereof, which will enable others skilled in the art to which it appertains to make and use the same, reference being had to the accompanying drawings, and to the reference-numerals marked 15 thereon, which form part of this specification.

Our present invention relates to a dispensing device whereby paste or other semi-20 liquid material may be discharged from a receptacle as required. Our device is especially adapted to and is illustrated and described herein as being used as a dispensing device for tooth-paste and is used in connection with a tooth brush. It will be understood, however, that our invention is not limited to use with toothpaste but may be used in a great variety of ways such as, 25 for shaving cream, semi-liquid soap, ointments and various other toilet and medicinal preparations. While our article is here illustrated in connection with a tooth brush it will be noted that it may be readily used without the tooth brush attachment and is 30 a complete article without the tooth brush.

The purpose of our invention is to provide a dispensing device of the class described which is simple in construction and operation, durable and sanitary in use and capable of being applied to many uses.

Another object of our invention is to provide a dispensing device wherein a yielding or spring tension or pressure is imparted to the paste in the receptacle whereby an improved mechanical action is obtained and economy and convenience in the article are likewise obtained.

A still further purpose is to provide an article of the class described wherein a coiled 50 spring is used in connection with a plunger back of the material in the receptacle to obtain a spring pressure tending to gently force the material from the receptacle; and furthermore to provide in connection with 55 said spring and plunger such a combination

and arrangement of the parts as are well adapted to provide an improved dispensing device; a still further purpose is to provide in connection with the coiled spring and plunger means whereby the tension of the 60 spring may be readily varied at will obviating excessive pressure when the receptacle is full and maintaining sufficient pressure to force all material from the receptacle in proper manner.

Further purposes and advantages of our invention will appear from specifications and claims herein.

Figure 1 is a view partly in side elevation and partly in longitudinal section of 70 a dispensing device embodying our invention in a form adapted for use separate from any other article.

Fig. 2 is a side view of a tooth brush equipped with a tooth-paste dispensing device embodying our invention.

Fig. 3 is a view of the same mostly in a longitudinal section and showing the piston in retracted position.

Fig. 4 is a longitudinal sectional view on 80 an enlarged scale of the second form of our dispensing device with the piston advanced part way through the cylinder.

Fig. 5 is a side view of the cylinder forming the paste-receiving receptacle on a similarly enlarged scale.

Fig. 6 is a longitudinal sectional view of the casing housing the coiled spring on the same scale as Figs. 2-3.

Fig. 7 is a side view of a portion of said 90 casing on an enlarged scale with its interior-screw-threaded arrangement shown in dotted lines.

Fig. 8 is a side view of the piston.

Figs. 9 and 10 are front end and side views 95 respectively of the sleeve to which is attached the rear end of the coiled spring.

Fig. 11 is a side view of the shaft piece.

Referring to the drawings in a more particular description it will be seen there is 100 provided a receptacle cylindrical in form and hereinafter call the paste-receiving cylinder 15, provided with a forward opening 16 of reduced diameter and with its rear end open for the full interior diameter of the 105 cylinder. The outside of the cylinder 15 is knurled at its extreme rear end 17 for a purpose to be hereinafter described and forward thereof or to the left as shown in the drawings is provided with a screw-threaded por- 110

tion 18 of slightly larger diameter than the knurled portion 17.

Removably and slidably mounted in the bore of the cylinder 15 is provided the piston 19 of such diameter as to closely fit said cylinder and force material in said cylinder forward and out of its forward opening 16 as the piston 19 is moved forward.

To the rear of said piston 19 is attached 10 the forward end of a coiled spring 20 as by means of the forward coil of said spring being made of reduced diameter so as to hold itself in the annular recess 21 provided on the side of a projection 22 upon the rear face 15 of the piston 19.

A hollow casing 23 is provided adapted to house the coiled spring in the cavity of said casing. The forward end of this casing 23 is secured preferably in a detachable manner 20 to the cylinder 15 as by the forward end of said casing being provided with internal screw threads 24 adapted to engage the external screw-threaded portion 18 on cylinder 15. Slightly back from its front end or left 25 end as seen in the drawings and close to the extreme rear end of the cylinder 15 the casing 23 is provided with an inwardly extended projection adapted to cooperatively engage one of the coils of the coiled spring 30 20. Preferably this inwardly extending projection will be formed as an inwardly extending ring 25 provided on its inner surface with a groove 26 spirally disposed to form a screw-threading through which will play 35 a coil of the coiled spring 20 as the said spring is rotated. The cavity 27 in said casing to the rear of the screw-threading 26 is of a diameter to contain the coiled spring arranged longitudinally in the casing and 40 said chamber cavity 27 is of sufficient length to house substantially all of the spring when it is in retracted position as appears from Fig. 3 of the drawing. It will be understood of course that the rear end of the coiled 45 spring is held within the casing 23 and that rotative movement is imparted to said coiled spring by means engaging the rear end of the spring and operated from without the casing. These means include a sleeve 28, a 50 shaft 29 and a disk 30. The sleeve 28 is rotably mounted in the central aperture provided in the right end 31 of the casing 23 and is provided at its forward or left end portion with the flange 32 adapted to bear 55 against the inner face of said casing end. Through the sleeve 28 extends the shaft 29, the two parts being secured to rotate with each other as by means of a pin 33 extending through said two parts. The rear end of 60 the shaft 29 projects beyond the sleeve 28 and the rear end of the casing 23 to receive the disk 30 which is fixed to said projecting end of the shaft by any proper means such as a pin 34 extending through said disk and shaft. 65 The flange 32 upon the sleeve 28 is provided

with a longitudinal extending recess 35. Beyond the flange 32 of the sleeve 28 the shaft 29 has a short and slightly enlarged portion 36 and therebeyond is provided with a further enlargement 37 preferably of sufficient length to extend merely to the screw-threaded inward projection 25 of the casing 23. This enlargement 37, preferably hollow as indicated in Fig. 11 for the sake of lightness, serves as a guide inside that portion of the spring 20 that may at any time be in the cavity 27. The rearmost coil of spring 20 is formed with a reduced diameter fitting into the recess provided outside the portion 36 on shaft 29 between the rear end of the enlargement 37 and the forward face of the flange 32 on the sleeve 28. In this way the rear end of the spring is held from movement longitudinally of the said shaft and sleeve. Rotative movement is imparted to 75 the spring through the rear end 38 of said spring being bent to be parallel with the axis of said spring and closely fit into the slot 35 in the flange 32 of sleeve 28.

It will now be seen that rotation of the 90 knurled disk 30 in one direction will operate to screw the coiled spring 20 forwardly through the screw-threading 26 and that thereupon the portion of said spring forward of said screw-threading will tend to expand and will exert a spring pressure against the piston 19 tending to force said piston forward and therefore forcing the paste or other semi-liquid material from the cylinder 15 out through the forward opening 16. 95

It will also be seen that rotation of the knurled disk 30 in the opposite direction will operate to screw the coiled spring 20 back through the screw-threading of the casing 23 gradually withdrawing the piston 19 to the right as the parts are shown in the drawing and finally withdrawing the said piston entirely from the cylinder 15 to the position shown in Fig. 3 of the drawings with substantially all of the coiled spring 105 housed under compression in the cavity 27 of the casing.

With the piston in this retracted position the casing 23 may be readily detached from the cylinder 15, exposing to view the open 115 rear end of the cylinder 15 which may be readily re-filled with a fresh supply of paste or other semi-fluid material. Thereupon the casing 23 will be again attached to the cylinder and the rotation of the knurled 120 disk 30 will operate to have the piston 19 again enter the bore of the cylinder 15.

It will now be seen that we have provided a dispensing device of improved form and well adapted to attain the purposes pointed 125 out earlier in the specification and having the advantages above mentioned. It will be particularly noted that the pressure communicated to the piston 19 and thereby to the material in the cylinder is a spring or yield- 130

ing pressure and that the extent of said pressure may be regulated with great nicety. For this reason the device is well adapted to obtain a gentle flow of the material from the forward opening of the cylinder instead of the positive squirt that results where a positive pressure is imparted to semi-liquid material. And this yielding and regulated tension is also well adapted to overcome any 10 clogging of the paste in the receptacle without breaking the device or wasting the material.

It will also be noted that the device described is "fool-proof" at both extreme positions. When the piston has been forced forward to the full extent there will be no danger of breaking the device through further rotation of the disk 30 under ordinary conditions for the reason that under these circumstances the disk will rotate backward under the spring tension from the spring as soon as the operator releases his hold upon the disk for the purpose of further rotating the disk. Similarly when the piston has been entirely retracted, the continued rotation of the disk 30 will do no damage as the disk 30 will rotate in a reverse direction as soon as the operator removes his hand from the disk.

It will be noted that we have so far described our device without reference to the particular material that is used in the device and entirely without reference to the tooth brush shown in the drawings as attached to the dispensing device. It will be seen therefore that our device is entirely operative as a dispensing device as already described, it being understood simply that when used as a separate dispensing device a cap or other proper closure will be provided for the forward opening 16 of the device in order to prevent the material from leaking or drying out.

The dispensing device herein shown may be readily used in connection with a tooth brush to provide a magazine supply of tooth paste. For such use we provide a forward case 39 adapted to inclose the cylinder 15 except for the forward end 16 of said cylinder. The rear end of this casing 39 is provided with interior screw threading, fitting the screw threaded portion 18 of the cylinder 15. Upon this casing 39 may be pivotally mounted the handle 40 for a tooth brush 41. The tooth brush may be swung out of line with the cylinder to receive paste from the cylinder as shown in Fig. 3 and then may be swung back into line with the cylinder as shown in Fig. 2 presenting the tooth brush for actual use with the case 39 and casing 23 forming a long handle for the brush.

As the details of construction and operation of this brush have formed the subject 65 matter of a co-pending application further

description thereof herein is deemed unnecessary.

The purpose of the knurling upon the rear end 17 of the cylinder 15 is to afford ready means for unscrewing the cylinder 15 from the outer casing 39 after the casing 23 and piston 19 have been detached from the device. The cylinder 15 will be thus removed from the outer casing 39 where a fresh supply of material is provided already packed in another similar cylinder 15. Our dispensing device is well adapted to be used in conjunction with tubes of tooth-paste or the like packed in cylinders similar to the cylinders 15. It will be seen that the cylinder 15 is similar to the commercial form of tubes containing paste and requires only the addition of the threaded portion 18, a removable stopper for the open rear end of the cylinder and preferably a knurled section 75 at the extreme end of the cylinder beyond the threaded portion.

Where ready packed tubes of paste are not available in the form of cylinders 15, the cylinder 15 of our device will be retained 80 as a permanent part of the article and refilled when desired from a suitable source of supply by removing the casing 23 and piston 19 from the cylinder as already described.

What we claim as new and desire to secure by Letters Patent is:

1. In a device for dispensing paste or the like, the combination of a paste-holding cylinder having a discharge opening at its forward end, a piston adapted to slide in said cylinder and force the material forward therefrom as the piston moves forward, a coiled spring attached at its forward end to the rear of the piston and adapted to enter said cylinder, a hollow casing secured to the rear end of the cylinder and housing said coiled spring and provided with an inwardly extending projection near its forward end to engage said coiled spring and means operated from without the casing for rotating said spring whereby longitudinal spring pressure is imparted to the piston.

2. In a device for dispensing paste or the like, the combination of a paste-holding cylinder having a discharge opening at its forward end, a piston adapted to slide in said cylinder and force the material forward therefrom as the piston moves forward, a coiled spring attached at its forward end to the rear of the piston and adapted to enter said cylinder, a hollow casing secured to the rear end of the cylinder and housing said coiled spring and interiorly-screw-threaded near its forward end to engage said coiled spring and means operated from without the casing for rotating said spring whereby longitudinal spring pressure is imparted to the piston.

3. In a device for dispensing paste or the

like, the combination of a paste-holding cylinder having a discharge opening at its forward end, a piston adapted to slide in said cylinder and force the material forward therefrom as the piston moves forward, a coiled spring attached at its forward end to the rear of the piston and adapted to enter the rear of said cylinder and move forwardly therein, a hollow casing detachably secured to the rear end of the cylinder and housing said coiled spring and provided with an inwardly extending projection near its forward end to engage said coiled spring and means operated from without the casing for rotating said spring whereby longitudinal spring pressure is imparted to the piston.

4. In a device for dispensing paste or the like, the combination of a paste-holding cylinder having an open rear end and a discharge opening at its forward end, a piston

adapted to slide in said cylinder and force the material forward therefrom as the piston moves forward, a coiled spring attached at its forward end to the rear of the piston and adapted to enter the rear of said cylinder and move forwardly therein, a hollow casing detachably secured to the rear end of the cylinder and housing said coiled spring and interiorly-screw-threaded near its forward end to engage said coiled spring and means operated from without the casing for rotating said spring whereby longitudinal spring pressure is imparted to the piston and the piston may be withdrawn from the cylinder.

In witness whereof we have affixed our signatures this 1st day of March, 1919.

THOMAS E. BARNES.
BREWSTER C. SHETTER.
